(Cl. D86—10)

To all whom it may concern:

Be it known that I, Emile Norman, a citizen of the United States and a resident of the city of El Monte, in the county of Los Angeles and State of California, have invented a new, original, and ornamental Design for a Cap for Lipstick Holder or the like, of which the following is a specification, reference being had to the accompanying drawing forming a part thereof.

On the drawing:

Figure 1 is a perspective view of a cap for lipstick holder showing my new design; and

Figure 2 is a perspective view of the same looking at it from its other end and from an opposite side.

I claim:

The ornamental design for a cap for a lipstick holder or the like, as shown.

EMILE NORMAN,
